UNITED STATES PATENT OFFICE.

EDWARD S. MCKINLAY, OF DENVER, COLORADO, ASSIGNOR TO MCKINLAY MINING AND LOADING MACHINE COMPANY, OF DENVER, COLORADO, A CORPORATION OF COLORADO.

COAL MINING AND LOADING MACHINE.

Application filed April 26, 1923, Serial No. 634,909. Renewed January 21, 1926.

The present invention relates to improvements in coal mining and loading machines, in which provision is made for digging or excavating coal from the mine and transferring it immediately and automatically to a point removed from the scene of the cutting operations where it is loaded upon cars or other vehicles for transportation out of the mine.

10 The invention consists in certain improvements on my prior machines and consists in one aspect in certain reorganizations of the parts and mechanisms contributing to a more compact, strong and durable machine capable of being manufactured at reduced costs, while performing certain auxiliary operations, hereinafter described, which improve the character of work performed by the machine and which, furthermore, decrease the 15 cost of coal mining, eliminate a large part of the hand labor heretofore required, promote safety in the mining and generally result in a more practical and satisfactory method of mining and loading the coal.

20 With the foregoing and other objects in view, the invention will be more fully described hereinafter, and will be more particularly pointed out in the claims appended hereto.

25 In the drawings, wherein like symbols refer to like or corresponding parts throughout the several views,

Figure 1 is a top plan view, with parts broken away showing an improved machine constructed according to my invention.

Figure 2 is a side elevation thereof.

Figure 3 is a front elevation of the machine.

Figure 4 is a horizontal section taken on the line 4—4 in Figure 3.

Figure 5 is a vertical, central and longitudinal section through the machine.

Figure 6 is a vertical transverse section taken on the line 6—6 in Figure 2.

45 Figure 7 is a similar section taken on the line 7—7 also in Figure 2.

Figure 8 is likewise a cross section taken on the line 8—8 in Figure 2.

Figure 9 is a fragmentary top plan view showing the extension conveyor.

50 Figure 10 is a side view of the same.

Figure 11 is also a fragmentary top plan view showing how the auxiliary frame may be turned at right angles.

Figure 12 is a cross section taken through 55 the conveyor, and showing a modified form of roller support.

Figure 13 is a front view with parts shown in section showing a vertically reciprocating saw frame and with the frame in the upper 60 position.

Figure 14 is a similar view of the frame in the lower position.

Figure 15 is a fragmentary side view of the device shown in Figure 13.

Figure 16 is a fragmentary side view showing the slot cutters.

Figure 17 is a plan view of the same indicating in dotted lines the extended position of the slot cutters.

70 Figure 18 is a fragmentary front view of a modified form of machine showing two rotary cutter heads in combination with bottom slot cutter.

Figure 19 is a vertical section taken on 75 the line 19—19 in Figure 18.

Figure 20 is a top plan view of the frame for the central slot cutter with the cutter chain omitted.

Figure 21 is a side view with parts broken 80 away showing a means for drawing dust from the mine or for furnishing fluid to the mine wall.

Figure 22 is a front view of the same.

Figure 23 is an enlarged section taken on 85 the line 23—23 in Figure 21.

Figure 24 is a modified form of cutter head.

Figure 25 is a front view, with parts broken away showing a still further modified 90 form of cutter head.

Figure 26 is a cross section taken on the line 26—26 in Figure 25 and shown on an enlarged scale.

Figure 27 shows a front view of the same.

Figure 28 is a fragmentary side view of a further modified form of cutter head.

Figure 29 is a perspective view of the same on an enlarged scale.

Figure 30 shows a fragmentary side view 100 of the cutter head showing an improved form of scoop with an adjustable gate.

Figure 31 is a perspective view of the same on an enlarged scale.

Figure 32 is a side view of the cutter head having improved scrapers thereon.

5 Figure 33 is a rear elevation showing the same.

Figure 34 is a perspective view of a cone for use on the cutter head.

10 Figure 35 is a similar view showing an elevation of a modification.

Figure 36 is an end view thereof.

Figure 37 is a fragmentary side view showing the cutter head with an adjustable breaking disc.

15 Figure 38 is a section taken on the line 38—38 in Figure 37.

Figure 39 is a diagrammatic view showing how three cutter heads may be mounted upon a machine and indicating the several circles 20 of operation.

Figure 40 is a fragmentary plan view showing the bearings at the point of connection between the shafts and the cross bar connected to the hydraulic mechanism.

25 Figure 41 is an enlarged section taken on the line 41—41 in Figure 40.

Figure 42 shows a longitudinal section taken through the motor shaft, and

30 Figure 43 is a transverse section taken on the line 43—43 in Figure 42.

35 Referring more particularly to the machine shown in Figures 1 to 8 inclusive of the drawings, the machine comprises generally a frame work composed of pairs of upper and lower longitudinal rails 1 and 2, which are spaced apart horizontally and vertically, the upper pair of rails 1 being preferably extended to the rear beyond the lower rails, and said lower rails are supported for rolling movement in the mine upon the rollers or wheels 3 and 4. These rollers are shown in Figure 1 to extend beyond the sides of the frame work in order to give a better balance to the machine and said rollers are journaled upon shafts 5 and 6 carried by bearings affixed to the lower rails 2.

40 The upper rails 1 are appropriately supported from the lower rails as by the use of posts 7, 8 and 9 at suitable intervals; and the upper and lower pairs of rails are secured together horizontally by an appropriate number of horizontal braces. The framework is otherwise braced or trussed as may be desired to meet the requirement of strength.

45 At the front of the machine are mounted a number of cutter heads, in this form of the invention shown to be two in number and designated at 10 and 11, the cutter heads carrying a number of cutters spaced radially apart and adapted to be rotated from shafts 12 and 13 which extend in parallel relation at opposite sides of the frame work of the machine and are journaled in bearings for instance carried by the posts 7 and 9. These

50 shafts occupy a substantially intermediate position with respect to the height of the frame and they are driven by appropriate gearing which receives its source of motion from an electric or other motor 14 mounted upon the frame preferably at the upper forward portion thereof.

55 As shown the shaft 15 upon which the armature of the motor is mounted extends to both sides above the shafts 12 and 13, said motor shaft being transverse of, or at right angles with respect to, the cutter shafts 12 and 13, and having keyed or otherwise affixed thereto a pair of worms 16 and 17 disposed in mesh with worm wheels 18 and 19 keyed or otherwise secured to the cutter shafts below the worms. The shafts 12 and 13 thus receive rotary movement from the motor or drive shaft 15 and are rotated in opposite directions.

55 The cutter heads 10 and 11 are secured to rotate in any appropriate manner with the oppositely rotating shafts 12 and 13 and the cutter heads 10 are probably in the nature of

60 flat bars extending diametrically to opposite sides of the shafts and having a number of cutters 20 and 21 provided with toothed or serrated cutting edges for taking into the coal vein or wall of the mine. As shown in

65 Figure 3 the cutters partake of the same curvature as coincides with their radial distance from the centers of the shafts 12 and 13, the curvature therefore being sharpest for the innermost cutters, the outer cutters progressively flattening to a greater extent,

70 this for the purpose of causing the cutters to bite into the coal vein in true circular paths without encountering any lateral strains upon the cutter blades and without tearing or shearing the coal. The result

75 produced in the coal vein by the rotation of the radially separated cutters is a number of concentric rings in the face of the coal which on attaining a suitable depth by the cutters

80 are intended to be broken off and to fall to the bottom of the mine in front of the machine where they will be lifted by scoops 22 and 23, carried by the rear faces of the cutter heads 10 and 11, such coal being deposited

85 by the scoops or shovels or pusher plates on to a hopper by which the coal is fed to a conveyor for transferring the same to cars or other vehicles by which it is transported

90 out of the mine.

95 The breaking of the rings of coal is accomplished by suitable devices carried by the cutter heads. Each cutter head carries a centering and boring bit 24 which constitutes an extension of a cone 25 disposed

100 against the forward face of each cutter head and in alignment with the cutter shaft. The cone 25 progresses into the center of the innermost and smallest ring of

105 coal which is cut out by the bit 24 and the two cutter blades nearest the center of the

110

115

120

125

- cutter head, and as this cone moves into the coal ring it will exert a pressure due to its enlarging diameter and the coal will thus be broken from the vein as the pressure exerted thereon is at right angles to its connection with the coal bed and directly opposite to the outer side of the ring which has been removed and cut away by the action of the cutters.
- 10 The cutter head 10 carries a disc 26, which is secured thereto by an appropriate bracket located at the edge of the cutter head 10 which is the rear or trailing edge as respect the direction of rotation. The wheel or disc 26 is adapted to rotate and it is shown as substantially in alinement with the second cutter blade from the center upon one side of the cutter head and as seen in Figure 3 this disc or wheel is substantially straight 20 with reference to the curved character of the adjacent cutter blades and the disc may be given any angular tilt or position desired in order that it may exert a sidewise pressure against the second concentric ring thus 25 tending to break this ring and cause the coal composing the same to fall to the bottom of the mine. In a similar manner the other side of the cutter head 10 carries a similar disc 27 which is also mounted upon the rear 30 or trailing edge of the cutter head and is therefore seen in Figure 3 to be disposed on a relatively opposite edge of the disc. The disc 27 is also located a greater distance from the center of the cutter head and opposite 35 the third cutter blade in order to sever and break off the outermost concentric ring of the coal. The other cutter head 11 is similarly equipped to cause breaking of the rings of coal cut out thereby.
- 40 The scoops or shovels 22 and 23 carried by the rear edges of the cutter heads are provided with rear openings 28 adjacent inwardly curved walls 29 which direct the coal toward the openings 28 upon the arrival of 45 the scoops at an uppermost position and in this uppermost position the openings 28 in the scoops are disposed to direct the coal out of the openings 28 and upon troughs 30 and 31. The troughs 30 and 31 are mutually inclined and are fixed to the outer posts 7 of the frame work or to other appropriate parts. The inner and lower ends of the troughs are arranged to deposit the coal upon the chute 32 having its forward and 50 upper part disposed beneath the troughs as shown to best advantage in Figures 5 and 6, the trough inclining downwardly and converging rearwardly and having flanges 33 at its sides to avoid the escape of the coal therefrom.
- 55 These flanges further serve to guide the coal into the constricted neck of the chute where it is deposited upon a belt conveyor 34. The conveyor extends longitudinally of the frame and its forward portion lies be- 60
- neath the discharge mouth of the chute 32 and at this point it is desirable to have confining walls 35 at the sides of the discharge mouth of the trough and just above the conveyor belt in order to guide the coal on to the belt and to place it and fix it before the belt moves with its load away from the receiving point. This construction is shown most clearly in Figure 7 and this construction avoids the spreading of the coal upon 70 the conveyor and its spilling over the sides after the conveyor moves from under the confining walls 35, which are suitably suspended by brackets or arms 36 from the frame work.
- 75 A second chute 37 is provided beneath the upper chute 32, said lower chute sloping in an opposite direction or upwardly from the front of the frame work back over the forward part of the conveyor 34. The 80 lower and wider portion of this lower chute 37 is disposed close to the bottom of the mine for the purpose of catching the material upon the floor as the machine moves into the retreating wall of the vein. The 85 coal upon the floor of the mine is thus forced up the inclined lower chute 37 until it is caught upon the conveyor 34; it being understood from Figure 6 that the lower chute also converges to a point above the 90 conveyor belt and is provided with side walls 38 the outer ends of which are secured for instance to the front posts 7. The base portions of the front post 7 are 95 also utilized to hold the wings 39 and 40 which shoves the coal lying in the bottom of the mine ahead and out of the path of the rollers 3. These wings have curved under walls in order to allow the coal to escape past the same when it has been shifted 100 out of the direct path of the rollers.
- 105 Now it will be appreciated from Figure 3 that the two rotating cutter heads will cut out from the coal vein or wall two circular cavities leaving material above and 110 below adjoining the point of tangency of the two circles and these portions being substantially triangular in shape. It becomes desirable and necessary therefore to cut out these triangular portions and to accomplish 115 this I propose to provide a pair of upper saws 41 and 42 and a pair of lower saws 43 and 44, all of which saws are carried by a horizontally reciprocating frame work 120 mounted at the front portion of the machine and being of a substantially open or rectangular construction having the inner side portions engaged by eccentrics 46 and 47 keyed to the shafts 12 and 13 as shown in Figure 6. It will be noted that the eccentrics 125 are offset approximately 180 degrees in order to provide for the movement of the frame first to one and then to the other side in order that the saws connected to the frame may be made to partake of the 130

reciprocating movement necessary to cut through the triangular portions of the coal left untouched by the rotating cutters.

The frame 45 is held in place by clips 5 48 and 49 slidably engaged with the upper and lower bars of the frame and being bolted or otherwise secured to the cross bars 50 and 51 which extend between the front posts 7.

10 It will be noted that the bars 50 and 51 are flanged or of angle iron construction and the frame is supported upon rollers 52 which are carried by said frame and rest upon the horizontal flange of the upper bar 15 50 across which they are adapted to roll. Moreover other rollers 53 carried by the upper portion of the reciprocating frame 45 roll in contact with the vertical flange of the upper bar 50 and act to steady and guide 20 the movement of the frame.

In a similar way lower vertical rollers 54 move in contact with the horizontal flange of the lower rail 51 and lower horizontal rollers 55 lie in contact with the vertical depending flange of said lower rail 51. By the use of the clips and these rollers the frame is adequately secured in place while at the same time being free to move transversely with the greatest ease. The arrangement 30 also reduces the friction to a minimum.

Now referring more particularly to the conveyor construction, the front portion of the conveyor extends about the forward shaft or axle 5 upon which the rollers 3 35 are mounted and the conveyor belt is preferably engaged with a roller 56 at this point. Thence the conveyor extends back and upwardly in a generally diagonal direction and the rear end of the conveyor engages over a 40 roller 57 upon a shaft 58 which is journaled in appropriate bearings upon the rear extended ends of the upper rails 1. Adjacent this roller 57 is a companion roller 59 engaging the upper run of the belt near the 45 roller 57, said roller 59 being supported upon a shaft 60 also carried by the upper rails. Closely adjacent the roller 59 is an idler 61 at a lower elevation engaging the lower run of the belt and guiding it to the 50 roller 57. The idler 61 is carried by a shaft 62 which is journaled in the side portions of the upper rails 1.

The driving connections for the belt are placed intermediately thereof and consist in a friction driving roller 63 mounted upon a shaft 64 carried by an appropriate part of the frame work and at a suitable elevation to engage beneath the lower run of the belt at a point opposite one or more pressure 55 rollers 65 which extend between the two runs of the belt and which are forcibly pressed against the lower run of the conveyor belt and which in turn forcibly press the conveyor belt against the driving roller 63. A 60 guide roller 66 is placed above and adjacent

the driving roller 63 and engages beneath the lower run of the belt and is so positioned and arranged as to guide the two runs of the belt closely together and to force the lower run of the belt about an extended area of the 70 surface of the pressure roller 65 in order to secure comparatively great traction at the driving point. The pressure roller 65 is carried upon a shaft 67 carried in the ends of a pair of arms 68 which are pivoted as indicated at 69 upon the intermediate part of the vertical posts 8. The opposite ends of these arms are engaged with coil springs 70 connected to eye bolts 71 passing through the upper rails 1 and having adjusting and lock 75 nuts 72 thereon for the purpose of regulating the tension of the springs 70 and consequently the degree of slippage of the belt 34 which governs its rate of speed. By loosening the tension of the springs 70 to the suitable degree the driving of the belt may be 80 entirely stopped.

Now the driving roller 63 is rotated by virtue of the connection of a worm 73 upon its shaft 64 with a worm wheel 74 secured 90 upon the cutter shaft 13. The electric motor 14 is therefore also the source of power for driving the conveyor.

The machine is intended to be held up 95 against its work and against the likelihood of backing off by the use of claw bars 75 and 76 which diverge rearwardly and are pointed or sharpened as indicated in Figures 1 and 5 to take into the side walls of the mine. These bars at their forwardly convergent 100 ends are coupled to a head 77 carried by the plunger 78 which fits into a hydraulic cylinder 79 carried beneath the upper portion of the frame work and preferably centrally thereof and longitudinally of the machine 105 so that the thrust exerted thereby will take place proportionately and uniformly upon both sides of the machine. The cylinder 79 slides in a yoke or stirrup 80 extending down from a cross brace 81 connected between the rear projecting ends of the rails 1. At the forward end of said cylinder 79, the same is coupled to a cross bar 82 as by the coupling member 83 or other device. The cross bar 82 extends transversely of the machine and in line with the cutter shafts 12 and 13 and bears against the rear ends of these shafts in order that the hydraulic pressure developed in the cylinder 79 may be realized through 110 these shafts directly upon the cutter heads, rather than through the frame work of the machine. Thus the entire weight of the machine is taken off the hydraulic apparatus and its function of keeping the cutter heads up to their work is greatly facilitated.

115 The operation of the apparatus thus far described is substantially as follows:—

The machine is rolled into the mine and moved up to its work with the blades upon the cutter heads 10 and 11 engaging the hori- 120 130

zontal wall of a coal vein. The claw bars 75 and 76 at the rear end of the machine are pushed forwardly until the plunger is all the way in the hydraulic cylinder 79, whereupon these claw bars are engaged with the side walls of the mine as indicated in Figure 1. Hydraulic pressure in a suitable amount is turned into the hydraulic cylinder 79 forwardly of the piston by the use of appropriate valves and connections which are not shown as they form no part of the present invention. The hydraulic pressure attempts to move the cylinder 79 forwardly as the piston is anchored against movement by the claw bars 75 and 76. The force of the hydraulic pressure is transmitted to the cross bar 82 and through the cutter shafts to the cutter heads thus holding these cutter heads against the wall of the coal vein and forcing the heads forwardly as the cutters round out the grooves between the concentric rings of coal.

The circuit through the electric motor 14 is closed and the motor driving the shaft 15 will communicate rotary movement to the cutter shafts 12 and 13 and a consequent rotary movement to the cutter heads. This movement will be in relatively opposite directions so that the strain of one cutter head will be absorbed by that of the other, and substantially equal reactions taking place, the strain upon the machine and other parts is reduced and properly compensated for.

The rotation of the cutter shafts 12 and 13 rotates the eccentrics which reciprocate the saw frame 45 and the upper and lower triangular portions of coal not reached by the circular blades will be cut into strips by the saws. The scoops or shovels carried by the rotary cutter heads constantly act to elevate the coal thrown upon the floor of the mine by the cutters and saws and this coal is deposited in the chute and delivered to the conveyor 34. The conveyor being also driven from the electric motor by the drive roller 63 conveys the coal to the rear of the machine and to a high elevation beneath which cars may be placed to receive the coal fed to this point. The machine advances automatically because of the hydraulic pressure and the action goes on until the cylinder 79 has moved to a position where the piston has arrived at the rear portion of such cylinder. At this point the claw bars 75 and 76 are disengaged from their old position and moved forwardly to be there reengaged with the mine wall in order that the hydraulic mechanisms may again come into play.

The machine is compact with the various agencies grouped closely together but not interfering with one another's activities and the electric motor is placed forwardly and at the upper part of the machine together with its drive connections in order that the weight

may be increased at this point where it is desired to stabilize the machine for resisting casual movement and the strains incident to the mining operation. The machine adequately takes care of all the coal cut by the use of the two cutter heads, the conveyor buckets and the conveyor and the drive mechanism for the conveyor is similarly easy regulable and secures high traction to avoid slippage of the belt even under the comparatively great loads required of it when handling coal.

Referring more particularly to Figures 9, 10, 11 and 12, 84 designates a pair of extension sills which form extensions of the upper rails 1 of the frame work of the machine and are secured to said upper rails as by the use of plates 85 bolted or otherwise secured as represented at 86. The extension frame is intended to carry the conveyor 34 rearwardly to a more convenient position for loading the coal into the cars or other vehicles represented in dotted lines at 87. The rear ends of the sills 84 are carried by posts 88 having rollers 89 similar to the rollers upon which the machine is carried in order that the frame work and the extensions may be movable as a unit in the mine. It will be noted that the extension lies well above the claw bars in order to avoid interference with the operation of the latter.

Now the conveyor 34 is spliced as indicated at 90 to the extension belt 91, this latter extension belt extending over the length of the extension frame and being trained over a roller 92 at its rearmost end. The lower run of this extension belt is supported by guide rollers 93 and 94 and a guide roller 95 upon the upper side of the lower run between the supporting rollers 93 and 94, forms a bight in the belt to keep the upper run taut. This upper run of the belt is supported upon a number of idlers 96 and 97 which are similar to the rollers 57 and 59 and are located on the extension frame adjacent to the latter rollers.

As shown by a comparison of Figures 9 and 11, the extension frame is adapted to be turned angularly with respect to the machine as for instance to pass around corners in the mine and for this purpose the extension frame carries a cross beam 98 having a forwardly extending central tongue 99 provided with a longitudinal slot 100 which communicates at its rear end with a transverse slot 101 in the beam 98. The two slots combine to form a substantial T. The rear part of the rails 1 carry a transverse plate 103 provided with a downwardly extending pin 102 which passes through the T shaped slot in the beam 98.

In moving the extension frame to an angular position, the plates 85 are first removed and the extension frame is dropped

which is permitted by unloosening the screws 104 in the socket 105 of the leg structure, which permits the socket members 105 to descend upon the posts 88 a sufficient distance to allow clearance by the extension sills 84 of the rails 1 and the extension frame may be thereupon turned angularly upon the pivot pin 102. It will be noted that the pivot pin in Figure 9 fits into the forward end of the tongue slot 100; while in Figure 11 it fits into one of the branches of the slot 101 in the beam 98. Should the extension frame be swung in the opposite direction the pin 102 would occupy the other branch. The extension frame may be made to assume any angular position and of course the lacing 90 is undone and the extension belt 91 has its free ends laced together so as to form a continuous and independent conveyor with its end extending beneath the end of the conveyor belt 34 so as to receive the coal therefrom. Any means may be employed for rotating the extension belt 91 and this may derive its movement either from the belt 34 or from an independent source of power.

Now in Figure 12 a modified form of supporting roller 106 is shown in which the conveyor belt 107 extends the full width of the roller and substantially the full width of the frame, the channel rails of which are indicated at 108 and 109 and these rails assist to guide the coal on to the belt 107 which assumes a curved shape transversely with its lower part in the middle and its ends highest whereby to guide the coal on to the belt and avoid its possible spilling over the sides. To effect this result the supporting roller 106 is of substantially elliptical form and being of less diameter in the middle and gradually increasing toward both ends thereof.

Referring more particularly to Figures 13, 14 and 15, there is here shown an arrangement of reciprocating saw frames 110 at the front of the machine which may take the place of the saw frame heretofore described. In this particular instance the saws 111 are arranged vertically instead of horizontally and the frame 110 is made to undergo a vertical reciprocating movement. In this instance the same eccentricities 46 and 47 are employed and they operate upon the upper and lower surfaces of recesses 112 and 113 made in the sides of the frame. In this instance the front posts 7 of the machine receive the guide rollers 114 and 115 carried by the frame and engaging respectively the side and front faces of the posts. The frame is held to the post by the use of clips 116 which permits the frame to freely move in a vertical direction. This vertically reciprocating saw frame may be used with or without rotating cutter heads and the saws will cut out the coal in relative-

ly thin vertical strips which can be broken off easily and removed by the conveyor or any other means from the mine. In case the saw frame is used without rotating cutter heads, it will be understood that cuts 70 will have to be made initially at the head and foot spaces of the vein in order to accommodate the end parts of the saw frame.

Referring more particularly to Figures 16 and 17, upper and lower chain slot cutters 75 117 and 118 are mounted at the sides of the frame and the forward ends of these chain slot cutters are carried by upper and lower shafts 119 and 120 journaled in appropriate bearings upon the upper and 80 lower rails 1 and 2. These shafts terminate short of each other and are provided with bevel pinions 121 and 122 which are in continuous mesh with opposite sides of the same bevel gear 123. These gears 123 are mounted loosely upon cutter shafts 12 and 13 and with the gears are provided clutch collars 124 cooperating with sliding clutch collars 125 which are keyed to the shafts and are moved into and out of engagement 85 with the clutch collars 124 by the use of levers or other suitable mechanism 126.

The slot cutters are preferably composed of chains having teeth thereon and these chains are pivoted about the shafts 119 and 120 and are adapted to swing out to the dotted line position shown in Figure 17 in order to cut slots in the side walls of the mine as the machine progresses. The slot cutters normally occupy a folded position 100 against the sides of the frame as shown in full lines in Figure 17 and are adapted to be gradually swung out by hand or automatic mechanism. One manner of doing this consists in the use of ratchet wheels 105 127 secured to the frames of the slot cutters and engage by escapements 128 which receive movement from levers 129 mounted upon the frame work. When the slot cutters are to be put in movement the clutch 110 120 is engaged so that the shafts 119 and 120 are driven and the slot cutters are gradually fed outward.

Referring to Figures 18, 19 and 20, a somewhat different form of machine is used 115 in which a central slot cutter is used at the base of the machine between the two rotary cutter heads. In Figure 18 the path of these cutter heads is indicated in broken lines which shows the substantially triangular space unaffected by the operation of the rotary cutters. At the base of this triangular space is provided the frame 130 which is secured to the machine in any appropriate manner and which carries a chain 120 125 131 provided with a number of teeth 132 projecting beyond the frame for the purpose of cutting into the coal vein. The frame may be of any shape desired and a preferred form is shown in Figure 20 in which 130

the frame is substantially rectangular having a triangular rear end and containing a number of sprocket wheels 133 over which the chain 131 moves. One of the sprocket 5 wheels is connected to a shaft 134 which extends upwardly to a suitable point as shown in Figures 18 and 19 and as provided at its upper end with a bevel pinion 135, which is driven by suitable gearing from 10 one of the cutter shafts for instance by the arrangement of gearing indicated in dotted lines. The frame 130 is provided with a number of rollers 136, and with advantage four such rollers are provided through 15 which the conveyor belt 137 is wound as indicated in Figure 19, the lower run of the belt being mounted over and under consecutive rollers. The forward end of the conveyor belt is thus brought directly beneath the ledge produced by the slot cutter and the coal is received directly upon the conveyor. It is noted that the conveyor belt is also by this means brought very close to the rotary cutter heads.

20 Coming now to Figures 21, 22 and 23, it is herein proposed to provide a means of sucking the coal dust and gases evolved in the mine through a suitable piping system or to pump fluid through this piping system to the working faces of the cutters and in carrying out this idea I prefer to make use of a hollow shaft 138 which carries the cutter head 139, the shaft 138 being driven by the electric motor or otherwise. 25 The shaft 138 is supported in a hollow bearing 140 provided with an annular channel 141 placed in communication with the interior of the shaft 138 through one or more perforations 143 in said shaft. The pipe 30 143 is coupled to the hollow bearing 140 and communicates with the annular channel 141. The pipe is adapted to convey off the gases and coal dust or is placed in communication with a source of fluid supply and a pump 35 may be used if desired to force the fluid through the pipe 143, or a fan or other suction device may be provided to create a partial vacuum in the piping system. The front end of the hollow shaft 138 is provided 40 with pipe branches 144 extending to either side and placing the interior of the hollow shaft in communication with conduits 145 and 146 which extend along the side edges 45 of the cutter heads 139. From these conduits lead tubes 147 and 148 which are disposed at the ends of the cutter blades 149, the open ends of the tubes terminating just short of the outer cutting edges of the blades 50 where they are in position to receive the coal dust and gases generated during the actual cutting operations.

55 Here these tubes are also well located to direct streams of fluid upon the coal vein and to wash down the cuttings.

60 65 In Figure 24 a modified form of cutter

head 150 is shown in which the bar of metal or other material of which the cutter head is made is twisted in reversely curved directions from the center 151 so that the entire cutter head conforms substantially to the figure 60 S or to an ogee curve. In this instance the cutter blades 152 are circumferentially shaped or curved to correspond with the curvature given the cutter head and corresponding further to their positions on 65 the cutter head and their relative location from the center 151.

The purpose of this shape is to throw the various cutter blades 152 in offset relation as respects radii of the cutter head as this 70 is particularly desirable where strata of dirt are encountered in coal mining operations. The S shape causes only one of the cutter heads to pass through the stratum of dirt at a time and the drag is preserved by the 75 remainder of the cutter blades on this side, of the cutter head so as to balance and oppose the action of the cutter blades on the opposite side of the head which are passing through the coal bed.

80 With reference to Figures 25, 26 and 27, the cutter head 153 in this instance is in the form of a hollow bar in which pairs of tubes 85 154 and 155 are mounted side by side and held in place as by the set screws 156 or other appropriate devices. The tubes 155 carry strands 157 of wire or other appropriate material and wire cable is found excellent for this purpose as the extremities 90 thereof form numerous sharp points adapted 95 to bite into the coal. The other tubes 154 are left open for the purpose of supplying fluid to the surface of the coal beside the cutting strands 157 or for conveying out the 100 coal dust and gases and for this purpose the 105 inner ends of the tubes 154 are slotted as indicated at 158, the slots being in communication with the interior of the hollow bar 153, and this bar is in turn in communication 110 with a source of fluid supply or a source of suction.

115 Coming now to Figures 28 and 29 a cutter head is shown at 159 and the blades at 160 and additionally I propose to provide upon one edge, preferably the trailing edge 115 of the cutter bar 159, an upwardly projecting cutter bit 161 which is preferably embedded in the cutter head or removably fitted in a socket provided therein and held as by a screw 162. The edge of the bit extends 120 outwardly beyond the edge of the cutter head to come in contact with the outer walls of the groove cut in the coal by the outermost cutter blade 160. This in fact acts as a reamer to enlarge the diameter of the outer 125 circle cut in the coal and thereby providing more room for breaking the rings of coal.

130 In Figures 30 and 31 the cutter head is indicated at 163, the cutter blades at 164 and the scoops or shovels at the back of the cut-

ter blades generally at 165. These buckets or shovels are provided with the openings 166 in the rear walls 167 and the bottom wall is sloping as indicated at 168 to direct the coal to the outlet 166 on the elevation of the bucket. The base 169 is secured against the rear face of the cutter head 163 by appropriate means and this base carries an adjustable end wall 170. The wall 170 is preferably adjustable by the use of a hinged connection 171 with the end of the base 169 and for purposes of effecting the adjustment and securing the gate or wall 170 in position under adjustment, a bolt 172 is used, said bolt having a hook 173 to engage over the outer edge of said gate and the bolt extending through an arcuate slot 174 made in the bottom wall. The bolt is adjusted by means of a nut 175 which is tightened to hold the gate in the adjusted position. This gate may be adjusted through a wide range as indicated in Figure 30 and controls the delivery of the coal to the conveyor so as to avoid the simultaneous dumping of too great a quantity of coal upon the conveyor such as would spill over the sides of the same and in general these devices provide for delivery of the coal in an even and uniform stream to the chute and to the conveyor.

33 As a modification of this idea the cutter heads 176 shown in Figures 32 and 33 are provided with scrapers 177 which are blades extending rearwardly from the cutting bars and having a sufficiently extensive radial area in order to sweep the coal after the manner of a broom upon the conveyor when the construction shown in Figures 18, 19 and 20 is employed. These scraper blades are attached to the cutter heads in any suitable manner as for instance by a flange.

15 In Figure 34 is shown the cone 25 which is carried upon each of the cutter heads at a central point. It will be noted that this cone has a uniform frusto-conical wall and is provided with a bore 178 to take the cutter shaft. An opening 179 may be provided in the side of the cone to take a pin for securing the cone to the shaft or the other appropriate part.

19 Figures 35 and 36 show a modification of this cone in which a cylindrical sleeve 180 is secured upon the shaft as by a pin or other connection and this sleeve carries the wedge shaped conical portions 181 and 182 diametrically opposite and between these portions are left spaces. In this case the action will be freer and it may be more desirable in certain circumstances and in certain characters of coal beds to use the interrupted cone rather than the full cone shown in Figure 34.

25 In Figures 37 and 38 the breaking disc indicated at 183 is carried in arms 184 projecting from a plate 185. The plate is provided with slots 186 for adjustment, screws

187 passing through the slots and into the cutter head indicated at 188. By loosening the screws 186, the breaker disc may be shifted back and forth to a desired position.

20 In Figure 39 I have illustrated how the machine may be provided in which three cutter heads 189, 190 and 191 may be used, each having its own circle of operation and provided with members of cutting blades as heretofore described. The end cutter heads 189 and 191 may be mounted upon the cutter shafts and the central cutter head 190 driven by a belt 192 or other mechanical arrangement from one of such cutter shafts. The machine may be made up of one or more of such cutter heads as will be obvious.

25 Referring to Figures 40 and 41, the cross bar 82 to which the hydraulic cylinder 79 and the cutter shafts 12 and 13 are connected is provided with races to receive ball bearings 193 which take against the ends of the shafts and act to reduce the thrust and to enable the shafts to turn freely although pushed axially by the strong hydraulic pressure.

30 In Figures 42 and 43 is indicated the electric motor 14 preferably having a tubular armature shaft 194 and slideable through this armature shaft is the worm shaft 15, keys 195 being provided to couple these two members in driving relation but allowing the shaft 15 to be adjusted through the sleeve 194. This is for the purpose of compensating for wear in the gearing and to permit the shaft 15 to adjust itself to irregularities in the gearing without causing any movement of the armature or parts of the motor.

35 It will be understood that the machine and the method of breaking out a core in small pieces may be applied to other uses than mining coal, and the improved belt conveyor, wedging devices combined with the hydraulic ram and other parts of the machine may be used separately or in other machines.

40 The wire end cutters will find a wide use not only in coal mining but also in ordinary drilling in earth, rock and other material. These wires as shown in Figs. 25, 26 and 27 are encased in tubes 155 which are preferably castings of soft metal possessing sufficient rigidity to sustain the wires in the cutting operation but adapted to wear down to constantly expose the ends of the wires for the cutting of the material.

45 The machine might be mounted on plates or shoes instead of wheels particularly where the floor was wet, muddy or slippery. The machine might be moved back and forth on wheels or plates or shoes without the use of jacks against the coal roof, floor or sides.

50 I do not desire to be limited to driving the conveyor, hydraulic pump and other devices on the machine from the one motor, as it may be best to use separate motor or motors.

55 There is one feature connected with my

coal mining machine to which I wish to call special attention, and that is my plan for cutting the kerfs entirely around the coal I propose to wedge down. Other machines

- 5 now in use, cut slots on the two sides and across the bottom and at the same time use auxiliary machinery to pick down the intervening coal and use a wedge in some form, to assist in breaking down the coal which
- 10 falls upon a conveyor which enters the bottom cut very similar to my plan, except that I propose to cut and wedge the coal by a different method and in a different way and to cut it all around instead of part way, and
- 15 to have it fall on the sides adjacent to the conveyor and then push the coal over from each side onto the conveyor.

Another thing regarding my plan of wedging and sawing out blocks is that by cutting out complete annular circles and wedging the coal out by the advance of the machine and the rotation of the cone or cams on the shank of the drill, I am able to make room for the cam action of the oscillating saws. While it is my idea to claim the wedging action through the advancing of the entire machine yet, independent of the machine's ram, other power to force in the wedge, without stopping the machine and increasing the pressure in the wedging tube, etc., may be used.

The cutting tools may be saws, steel tools, chain-cutters, ends of small wires etc. The revolving wedging breakers may be placed in front or behind the revolving cutters. The flanges on the hopper and guides where the belt runs close, to keep the fine coal on the belt, are lined with flexible material like narrow belting, riveted onto the sheet metal in order to prevent wear on the belt.

If the coal in passing up the lower inclined plate to reach the conveyor should clog or choke up no harm will result as the coal will pile up and gather until shovels reach it.

It may seem best to use the upper half section of saw frame cutting the top triangle at the rear of the machine so that the coal when cut will fall onto the moving conveyor belt. Although the front roller is shown on the axle this need not be the case and in actual practice it is preferred to have the roller forward of the axle.

Of course the pinch roller may be forced against the conveyor belt by any other means than the spring shown, as for instance by an eccentric device. Where screens, slats or buckets are used on the belt the pinch pulley will have to be made in two sections to allow the slats, buckets, etc. to pass through the center. The conveyor may be actuated by its own or separate motor.

The jacks or braces to hold against the hydraulic ram pressure may be set against

the top and bottom as well as the sides. The hydraulic pumps can be driven by separate motor, as well as by the machine's motor and gearing. The jacks holding against the sides or the top and bottom are moved back into their original position after a forward thrust by the ram, by reversing the pressure in the ram cylinder through the three-way valve, and as the machine is heavier than the jacks the latter pull up to their original position ready for another forward thrust. When it is desired to pull the machine back from the face the side-jacks are placed in the opposite position which then forces the machine back.

It is intended that the conveyor shall run at various angles of elevation according to the conditions existing, and as to how the material is disposed of at the back end. It may reach only to the back end of the frame, and at that point dump onto another belt conveyor which can swivel to any angle and carry the material to mine cars or to another belt etc. Or it may extend from the top of the frame directly back of the machine high enough for mine cars to be stored or held underneath ready for loading as the machine moves forward.

Light cross jacks running underneath the frame of the conveyor at the back end may also be used. These cross jacks carry rollers on which the frame moves forward and are held in level position as the machine moves forward. At the end of each stroke of the ram these cross jacks are moved forward.

The channel frame which carries the belt back of the machine is designed to be enough above the belt to prevent the material from falling off the belt.

In Figures 16 and 17 separate clutches on each vertical shaft may be used so that either one or both could be used.

Referring to the air suction device illustrated in Figures 21, 22 and 23, there may be an adjustable hood located at the front and on top of the machine frame which also connects with the suction pipe at the rear and which can be opened or closed at will to assist in removing gas, dust etc.

It is obvious that various changes and modifications may be made in the details of construction and design of the above specifically described embodiment of this invention without departing from the spirit thereof, such changes and modifications being restricted only by the scope of the following claims.

What is claimed is:—

1. A coal mining and loading machine comprising a frame mounted for movement, means for keeping said frame up to the work, cutter shafts journaled at the sides of said frame, cutter heads carried by said shafts and having radially displaced and curved blades for forming concentric rings

in the coal bed, breaker discs carried by said cutter heads in rear of certain of the blades, a central bit and an adjoining breaking cone carried by each of said cutter heads, buckets carried by the rear faces of said cutter heads and having openings in their rear portions with walls inclining to said openings, troughs carried by the front of the machine for receiving the dumpings from said buckets, a rearwardly inclined chute beneath said troughs, a second chute beneath said first mentioned chute and oppositely inclined, a conveyor carried by said frame with its forward end beneath both of said chutes confining walls adjoining the chutes and at the sides of the conveyor, and means for rotating said cutter heads and for driving said conveyor.

2. A coal mining and loading machine comprising a cutter head, a bucket carried at the rear side thereof and having a rear opening and an adjustable wall to restrict or enlarge said opening, and means to hold said movable wall in adjusted position.

3. An automatic mining machine comprising a rotary cutter head, a plurality of cutter bits projecting forwardly beyond said head for cutting a number of concentric rings of coal from the vein on rotation of the cutter head, and means also projecting forwardly beyond the cutter head and acting as the cutter head advances into the vein to press against the inner sides of the rings whereby to break the rings without interference from the cutter bits at the outsides of the rings.

4. An automatic mining machine comprising a rotary cutter head, means to rotate said cutter head, a number of spaced cutter bits projecting forwardly from said cutter head and adapted on rotation of the cutter head to cut from the vein a number of relatively narrow concentric rings, and wedging means also projecting forwardly from said cutter head and movable forwardly with the machine and cutter head into the kerfs cut by said bits, said wedging means engaging the inner sides of the rings and forcing the same outwardly to break out the rings as the cutter head is advanced into the vein without interference from the cutter head at the outer sides of the rings.

5. An automatic mining machine comprising a movable frame, oppositely rotating cutter heads at the forward part of the frame rotating toward one another at their lower portions to sweep the cut material toward the center of the front portion of the frame, cutter bits projecting forwardly from the cutter frame for cutting a number of narrow concentric rings from the vein on rotation of the cutter heads, means to rotate said cutter heads, and means active during the progress of the cutting action and pressing outwardly against the inner sides of

the rings for breaking out the rings, and means at the forward central part of the machine for receiving and removing the cuttings.

6. An automatic mining machine comprising a frame, a rotary cutter head thereon, means to rotate the cutter head, cutter bits projecting forwardly from said head to cut on rotation of the head thin concentric rings from the vein, a cone at the center of rotation of the head for entering the center of the innermost ring and wedging the ring outwardly from within, said cone projecting forwardly beyond the cutter head and the cutter bits being interrupted cylinders whereby they will not envelop the outer sides of the rings, and wedging means carried by the cutter head and projecting forwardly therefrom for engaging within each of the other rings whereby to break out the rings as the cutter head is advanced into the vein without interrupting the cutting operation.

7. An automatic mining machine comprising a frame, a rotary cutter head thereon, means on the frame to rotate the cutter head, spaced cutting bits projecting forwardly from the cutter head to cut concentric rings from the vein, a central cutter on the head, a cone in rear of the central cutter, said cone projecting forwardly from the cutter head to break out the inner ring without hindrance from the cutter head, said cone having removed side portions, and wedging means carried by the cutter head forwardly thereof to engage the inner sides of the outer rings and break the same outwardly as the cutter head rotates in the act of cutting into the vein.

8. An automatic mining machine comprising a frame, a cutter head rotatably mounted on the frame, means on the frame to rotate the cutter head, cutter bits projecting out from the head for cutting concentric rings from the vein, and angularly adjustable rotary cutting discs carried by said cutter head and projecting out from the head for wedging outwardly against the inside faces of the rings whereby to break out the rings without interference from said cutter head.

9. An automatic mining machine comprising a frame, rotary cutter heads thereon, cutter bits projecting forwardly from said heads to cut concentric rings from the vein, breakers also projecting out from said heads to break out the rings without interference from the cutter heads and simultaneously with the cutting operation, and transversely reciprocating saws carried by the frame for cutting out the portions of the vein above and below the zones between the circular fields of operations of the bits.

10. An automatic mining machine comprising a movable frame, a plurality of ro-

- ary cutter heads thereon, cutter bits projecting forwardly from said heads to cut concentric rings from the vein, wedging breaker means also projecting forwardly 5 from said cutter heads and free thereof for engaging the inner sides of the rings to break out the latter without interference from the cutter heads, a transversely-reciprocating saw frame on the movable frame of the machine 10 behind said cutter heads, saws on said reciprocating frame for cutting out the zones of the vein left between the circular fields of operations of the cutter heads, and means on the frame for rotating said cutter heads and reciprocating said frame.
11. An automatic mining machine comprising a movable frame, rotary spaced cutter heads thereon, cutter bits projecting forwardly from the cutter heads and being in radially spaced relation whereby to cut concentric rings in the vein, means also projecting beyond the cutter heads for wedging outwardly against the inner sides of the rings to break out the coal without interference 20 from the cutter heads, said cutter heads rotating in opposite directions and having their lower portions both sweeping mutually toward each other whereby to move the cuttings toward a central point, a cutter frame mounted between the cutter heads at approximately the floor of the mine, a traveling cutter carried by said frame, rollers carried by the interior of the frame, and a conveyor belt having its forward end engaged 25 with said rollers and adapted to receive the cuttings swept by the oppositely rotating cutter heads on to said cutter frame.
12. An automatic mining machine comprising a movable frame, rotary cutter heads carried thereby, bits projecting in radially spaced relation beyond the plane of the cutter head whereby to enter the vein without permitting entry of the cutter heads, said bits adapted to divide the vein into a number 30 of concentric rings, means also projecting forwardly beyond the plane of the cutter head for engaging the interior sides of the rings to force the rings outwardly and break out the same without interference from the cutter heads, shafts journaled in the sides 50 of said frame and connected to rotate said cutter heads, swinging side cutters comprising rotary substantially vertical shafts journaled in the sides of said frame, gearing between said vertical shafts, and the cutter 55 shafts, means for connecting and disconnecting the gearing, cutter frames adapted to pivot about said shafts at the upper and lower side portions of the frame, chains having teeth on the cutter frames adapted to be 60 driven from said vertical shafts, and means for swinging said cutter frames outwardly of the machine frame.
13. An automatic mining machine comprising a movable main frame, cutter shafts 65 journaled along the sides thereof and projecting forwardly from the machine and a motor mounted in the upper portion of the main frame and at a forward position thereof, gearing between the motor and shafts for 70 rotating the same in opposite directions, diametrically extending cutter heads on the shafts, curved bits in radially spaced relation projecting forwardly from said cutter heads for cutting concentric rings in the vein, wedge means also projecting forwardly from the cutter heads for engaging the inner sides of the rings to break out the rings during the 75 operation of cutting, a conveyor on the main frame adapted to receive the cuttings from the central forward portion of the machine, a transverse bar fitted against the rear ends of said shafts, antifriction thrust means in the bar engaging the shafts, and a hydraulic mechanism engaging the intermediate part 80 of the transverse bar for applying pressure directly to the cutter heads through the shafts for advancing the cutter heads into the work without first transmitting this movement through the machine frame.

EDWARD S. MCKINLAY.
